UNITED STATES PATENT OFFICE

STANLEY B. GAMBLE, OF OAKLAND, CALIFORNIA

BED-RAIL LOCK

Application filed April 29, 1926. Serial No. 105,368.

My invention relates to bedsteads and more particularly to a bed rail lock whereby the bed rails may be detachably secured to the bed posts of the bedstead.

5 One of the objects of the present invention is to provide a simple and efficient construction of a bed rail lock for securely fastening the bed rails to the posts of the bedstead.

Another object of the invention is to provide a novel form of bracket which is preferably made of a single piece of sheet metal and adapted to be secured to the bed post of the bedstead in combination with a novel form of a bed rail locking member whereby 15 the locking member engages the bracket to form a rigid connection between the bed rail and bed post.

A further object of the invention is to provide an improved form of a bed rail lock in 20 which the bed rail may be reversed or changed, end for end, so that the horizontal flange of the bed rail may be positioned on the top or on the bottom when attached to the respective ends of the bedstead when such a 25 change is required.

A further object of the invention is to provide a novel form of supporting bracket in which means are provided for detachably connecting a transverse brace rail which extends across the posts at the head and the 30 foot of the bedstead so that this cross rail may be dispensed with or attached according to the requirements.

Referring to the drawings, 35 Fig. 1 is a fragmentary side elevational view of a bedstead showing the manner in which my improved bed rail lock is employed,

Fig. 2 is an end elevational view of the bed rail lock shown in Fig. 1 with the bed 40 rail shown in cross section,

Fig. 3 is a top plan view of the construction shown in Fig. 1 with the bed posts shown in cross section,

Fig. 4 is a cross sectional view taken on the 45 lines 4-4 in Fig. 1,

Fig. 5 is the side elevational view showing a modified form of supporting bracket,

Fig. 6 is a cross sectional view taken on the 50 lines 6-6 in Fig. 5, and

Fig. 7 is the side elevational view of the

bed rail reversed end for end from the position shown in Fig. 1.

In illustrating one embodiment of my invention, I have shown the same in connection with a bedstead or bedstead post which is 55 in the form of metal square tubing, but it will, of course, be understood that the invention is applicable to metal round tubing as well as wooden bed posts. In carrying out my invention, I have shown my improved 60 form of supporting bracket 10 secured to the metal tubing or bed post 11. This bracket 10, I prefer to make of a single piece of sheet metal in the interest of economy in manufacture, but the same may be readily made in 65 the form of a metal casting.

In the preferred form, this bracket is provided with a vertically extending lock engaging wall 12 which in turn is provided with a vertically extending slot 13. One edge of the slot as shown at 14 extends in a vertical plane, while the other edge as shown at 15 extends at a slight angle with respect to the vertical, so as to form a bearing or camming surface for the locking member hereinafter described. The outer edge of the vertical wall 12 of the supporting bracket 10 extends in a vertical plane for the purpose of engaging the locking member in a manner herein- 75 after described. It will be noted that vertically extending edge 16 together with the inclined edge 15 forms a substantially vertically extending tongue as shown at 22'. The bracket 10 has one portion thereof secured to the bed post 11 by having one side as shown at 17 bent at right angles with respect to the lock engaging wall 12. This portion 17 sus- 80 tains the major part of the vertical strain on the bracket 10. Formed integrally with the lock engaging wall 12 and bent at right angles with respect thereto and also at right angles to the portion 17 of the bracket is a horizontal portion 18. Formed integrally with the portion 18 of the bracket 10 and at right angles with respect thereto is a lateral 85 portion 19.

This portion 19 is positioned in the same plane with the portion 17 and contacts with the post 11 to which these portions are secured by means of bolts 20 which extend through 90

suitable apertures in the post and engage threaded apertures in the metal strip 21 within the post.

It is quite obvious that means other than those shown in the drawing may be employed for securing the bracket to the post.

My improved locking member which cooperates with the above described bracket for securely and detachably locking the side rail to the bracket comprises a locking member 22 which is provided on one end with a lateral projecting tongue 23 which is arranged at right angles with respect to the main body portion of the locking member. Formed on the upper and lower ends of the locking member 22 adjacent the tongue 23 are two shoulders 24. The locking member 22 is secured to the bed side rail 25 by having the tongue 23 extend through a vertically extending rectangular slot 26 formed in the bed rail. The locking member 22 is held in spaced relation with respect to the side of the bed rail by having the shoulder 24 of the locking member engage the side of the bed rail as clearly shown in Fig. 3. The other end of the locking member 22 is held in spaced relation with respect to the side of the bed rail 25 by an offset portion 27 which is preferably pressed out laterally from the material of which the locking member 22 is made.

This locking member is secured in position against displacement from the side rail 25 by a rivet 28. This depressed or offset portion 27 is provided with tapered or camming surfaces 29 and 30 respectively. These camming or bearing surfaces 29 and 30 diverge with respect to each other so that the bracket is made reversible or more strictly speaking so that when it becomes necessary to change the side bed rail, end for end, so that the horizontal flange of the bed rail may be changed from the top to the bottom thereof or vice versa, these camming surfaces will engage the inclined surface 15 of the bracket and impinge or clamp the tongue 22' between the right angularly bent portion 30 of the locking member 22 and the camming surface 29 as clearly shown in Fig. 1.

From the above description, it will be seen that when the locking member 22 is attached or secured to the side rail 25 so that the horizontal flange 25' is on the top side thereof as shown in Fig. 1 and the offset portion with its camming surface 29 positioned to register with the slot 13 of the bracket 10, the vertically extending tongue 22' of the bracket 10 will register with the slot 23' formed between the member 22 and the side rail 25, and when the side rail is pressed into engagement with the bracket, the camming surface 29 engages the inclined surface 15 of the tongue 22' and impinges or locks the side rail 25 to the bracket in such a manner to form substantially a rigid connection between the post and the side rail, thereby eliminating

all possibility of vibration between these parts. It will also be noted that by reason of the relatively long camming or bearing surface 29 being in engagement with a corresponding length of surface 15, the possibility of wear on these surfaces is reduced to a minimum.

In Figs. 1, 2 and 3, I have shown a transverse brace 31 which extends between the posts and is in the form of an angle having one leg thereof secured by means of a rivet 33 to the horizontal portion 18 of the bracket 10. The other leg of the angle as shown at 34 is secured by the bolt 20 and contacts with the ear portion 19 of the bracket. The transverse brace is preferably bowed as shown at 34' so as to accommodate the bed spread so that the same may hang downwardly at both ends of the bed and cover the bedding.

In the modified form shown in Figs. 5 and 6, the horizontal portion 18 of the supporting bracket 10 is provided with a key hole slot 35 so as to permit the transverse brace 31 to be detachably secured to the bracket because in some bedstead constructions, this transverse brace is dispensed with and by having this transverse brace detachable, it may be readily taken off or if the construction of the bedstead requires it, it may be easily positioned and secured to the supporting bracket. The transverse brace 31 is provided with a pin 36 having a head thereon which is of relatively smaller diameter than the larger circular opening in the key hole slot 35 so that the head thereof may be readily slipped into the key hole slot and the lower leg 37 of the transverse brace member 31 secured to the bed post 11 by means of the bolt 20.

The operation of my improved bed rail lock will be apparent from the above description and the advantages arising from having a locking member with a relatively long bearing or camming surface contacting with a cooperating inclined surface of the tongue formed on the supporting bracket insures a firm locking connection between these detachable parts.

While in the above specification, I have described one embodiment which my invention may assume in practice, it will, of course, be understood that the same is capable of modification and that modification may be made without departing from the spirit and scope of my invention as expressed in the following claims.

What I claim as my invention and desire to secure as Letters Patent is:

1. In combination with a bedstead having a post, a side rail therefor, a tongue carried by said post, one edge of said tongue being inclined with respect to the other edge thereof, a locking plate having a right angularly bent portion engageable with one edge of said tongue and an offset camming portion engageable with the inclined edge of said post and the side rail, thereby eliminating

5 tongue, said rail being provided with a slot, a tongue on said bent portion lying in the plane thereof and forming a continuation thereof secured in said slot, and means extending through said camming portion for further securing said plate to the rail.

2. In combination with a bedstead having a post, a side rail therefor, a tongue carried by said post, a locking plate having a right angularly bent portion engageable with one edge of said tongue and an offset portion engageable with the other edge of said tongue, said rail being provided with a slot, a tongue on said bent portion lying in the plane thereof and forming a continuation thereof secured in said slot, and means extending through said offset portion for further securing said plate to the rail.

10 20 In witness of the foregoing I affix my signature.

STANLEY B. GAMBLE.
